UNITED STATES PATENT OFFICE

ARNOLD J. TANNER, OF NORTH HAVEN, CONNECTICUT

FOLDING PACKING AND DISPLAY CONTAINER

Application filed April 18, 1928. Serial No. 270,924.

The present invention relates to containers useful for packing and displaying merchandise of various kinds and the invention resides more particularly in certain improvements in the structure and design of the container whereby, at the minimum cost of production, an efficient packing and display container is provided. This improved container is simple in construction, therefore, the operation of assembling and setting the same up for packing and display purposes is accomplished with facility. The improved container is furthermore so constructed and designed that the same may be employed for various kinds of merchandise which may be packed singly in the container or a number of articles may be packed therein and readily dispensed therefrom.

The improved box consists essentially of an inner body portion and an outer enclosing sleeve or shell and which members are constructed of separate blanks. The novel features of the invention will be more clearly understood from the description which is hereinafter given with reference to the accompanying drawings wherein—

Figure 1 is a perspective view showing the complete container in its assembled condition and as set up in position for displaying merchandise which may be contained therein;

Figure 2 is a perspective view showing the container in its closed condition;

Figure 3 is an end elevation showing the container with the inner or body portion in a raised position;

Figure 4 is an enlarged view showing a modification of the improved container in cross section and as in its open position; and

Figures 5 and 6 are plan views of the pair of blanks of which one form of the improved container is composed.

Referring to Figures 5 and 6 of said drawings, herein are shown blanks 1 and 2 of which one form of the improved container is constructed. The blank 1 forms the body or inner member of the container and 2 forms the outer member or shell. The blank 1 is divided into a number of sections by parallel scored lines 3 and said sections are numbered 4, 5, 6, 7, 8, 9, 10 and in the other figures of

the drawings, showing the container in an assembled position, similar figures denote the parts of the box which each respective section forms. The section 6 has side wings 11 extending therefrom and this section 6 has a slot 12 cut therein and section 7 has slot 13 cut therein.

The blank 2 is divided into a number of sections by parallel scored lines 14 of which sections the central section is designated by numeral 15, intermediate sections by 16, and the end sections by 17. These end sections are reduced towards their ends so as to provide tongues 18 and these tongues are slotted at 19 so that the two end sections may be locked together to form the enclosing shell or member of the container. Upwardly extending wings 20 project from the intermediate sections 16 and the connection between these extensions and the body of the blank is scored on the lines 21 to permit folding over of the wings 20.

In assembling the container from the two piece blank, the first operation is to unite the ends of the shell member by means of the locking tongues 17 through the engagement of the slits 19. The body blank is then folded over on the scored lines 3 and the wings are turned upwardly. The body blank is then inserted into the folded shell member so that the section 6 forms the bottom of the container and the wings 11 bear against the end or side walls of the container. Said end walls are formed by the sections 16 of the blank 2. The section 15 forms the back wall of the container and the section 13 bears against the inside of said back wall. Section 8 of blank 1 forms the top cover of the container when the latter is closed. Section 9 covers the front of the container and section 10 is folded under the container and the tongue thereof engaged in the slot 12. The two sections 4—5 are folded over the reduced part of the sections 17, the section 5 being on the outside and section 4 on the inside and to retain this section 4 in its folded position, the same bears against the edges 26 of the projections 11.

It will be noted that the body or inner member, composed of the blank 1, is united

at the front end with the outer or shell member composed of the blank 2, by means of the section 5 folded over the front wall of the container and the section 4 folded downwardly behind the front wall. The back of the body member is not united with the shell and consequently, in such instances where desired, the bottom of the body may be lifted to an angular position as shown in Figure 3, with a hinge-like movement, the hinge being on the body itself and constituted by the scored bend 3 between the sections 5 and 6. Under ordinary circumstances, when the contents of the container are light in weight, the frictional contact of the body with the side walls of the shell is sufficient to retain said body in an angular or tilted position. When the box is partly folded, the sections 8, 9 and 10 constitute an upwardly extending portion or flap and this flap is arranged to be folded in the position shown in Figure 1 to form a display device at the back of the container. To insure that this display device is held in its upright position, the tongue 10 is engaged in the slot 13 and when so engaged, the tongue projects through the back wall of the body up against the back wall of the shell. This same retaining means can be utilized to hold the body in its tilted position for when the body is raised, said tongue will engage the upper edge of the back wall of the shell as shown in Figure 3. The flap formed by the sections 8, 9, 10 is further utilized to cover the open top of the container and the open front of the container. Said flap practically forms a wrapper around the container and when the tongue 10 is engaged in the slot 12, a very rigid and secure package is obtained.

Figure 4 illustrates a modification and herein the folded-over section is continued by adding the extension 23 which extends clear across the bottom of the container so that the free edge will abut against the back wall. This extension has the upwardly extending fold which may operate either as a partition or rack for the merchandise packed in the container.

It will be gathered from the above description of the invention that the improved container is simple in form and economical to manufacture. The simplicity is found to be of great advantage in the assembling and packing of the merchandise and the dealer desiring to utilize the container as a display medium for the goods contained therein can readily set the container up for display without necessity of reading directions and illustrations to show the proper method. In fact, the dealer cannot do otherwise than set up the box correctly.

Various modifications may be made in carrying out the details of the invention hereinbefore described and it is to be understood that any modification coming fairly within

the terms of the appended claims shall be covered thereby.

I claim—

1. A container of the class described having an inner body and a separate enclosing shell, said shell providing the back, front and side walls of the container, said body folding into said shell providing a bottom and a cover for the container, said body being united to said shell at the front end by means of a portion of said body being folded over the front and back surface of the front wall of said shell and self retentive means for retaining said portion in its folded position. 70

2. A container of the class described composed of a two piece blank, one blank forming an outer shell member and the other blank forming an inner body member, said shell member being scored to form a central, intermediate and end sections, said end sections being adapted to be united together to form the front wall of the container and said body member being arranged to fold into said shell and to be united therewith by means of sections of said body member folding over the front and back of the front wall of said shell. 80

3. A container of the class described composed of a pair of blanks, one blank forming the body or inner member of the container and the other blank forming the shell or outer member, said inner member being united with said shell member by folded portions of said body member extending over the front and back of the front wall of said shell member and self retentive means integral with said body member for retaining said portions in the folded position. 95

4. A container of the class described composed of a pair of blanks, one blank forming the body member of the container and the other blank forming a separate shell, said body member being united with said shell by a folded portion of said body member extending over the front and back of the front wall of said shell member, self retentive means integral with said body member for retaining said folded portion in the operative position, said body member having a folding portion forming a cover for the top and front wall of the container, means for retaining said folded cover portion in its closed position, said cover member being adapted to be folded back to form a display medium, means for retaining said display medium in an erect position and said body member being adapted to be moved and held in an angular or tilted position relatively to said shell member. 105

Signed at New Haven, county of New Haven, State of Connecticut this 17th day of April, 1928. 125

ARNOLD J. TANNER.
